(57) **CLAIM**

See application file for complete search history.

We claim the ornamental design for section of a rim for a feeder, as shown and described.

DESCRIPTION

FIG. 1 is a perspective view of the section of a rim for a feeder according to our design;

FIG. 2 is a top plan view of the section of a rim for a feeder according to our design;

FIG. 3 is a front plan view of the section of a rim for a feeder according to our design;

FIG. 4 is a side plan view of the section of a rim for a feeder according to our design;

FIG. 5 is a rear plan view of the section of a rim for a feeder according to our design; and,

FIG. 6 is a bottom plan view of the section of a rim for a feeder according to our design.

The broken line showing of FIGS. 1-6 of the section of a rim for a feeder is for illustrative purposes only and forms no part of the claimed design.
